ARTICLEJacob Wolf, Boston, Mass., assignor to Royal Jewelry Corporation, a corporation of Massachusetts

Application July 8, 1946, Serial No. 131,357

Term of patent 3½ years

(Cl. D45—19)

To all whom it may concern:

Be it known that I, Jacob Wolf, a citizen of the United States and a resident of Boston, in the county of Suffolk and the State of Massachusetts, have invented a new, original, and ornamental Design for Brooch or Similar Article, of which the following is a specification, reference being had to the accompanying drawing, forming a part thereof, in which

I claim:

The ornamental design for a brooch or similar article, substantially as shown.

JACOB WOLF.
